UNITED STATES PATENT OFFICE.

WILLIAM J. JACKSON, OF BROOKLYN, NEW YORK.

MACHINE FOR GRINDING AND REBORING ENGINE-CYLINDERS.

1,394,836.

Specification of Letters Patent.

Patented Oct. 25, 1921.

Application filed December 1, 1919. Serial No. 841,671.

To all whom it may concern:

Be it known that I, WILLIAM J. JACKSON, a citizen of the United States, and a resident of New York, borough of Brooklyn, in the county of Kings and State of New York, have invented certain new and useful Improvements in a Machine for Grinding and Reborning Engine-Cylinders, of which the following is a full, clear, and exact specification.

This invention relates more particularly to a class of apparatus adapted to be used in conjunction with engines.

My invention has for its object primarily to provide a machine designed to be employed for removing the deposits, such as carbonaceous substances, from the interior of the cylinders of internal combustion engines that accumulate during the operation of the engines for a period of time as well as being adapted for reborning the cylinders when occasion requires, and which is of a type enabling the work to be accomplished with great facility and accuracy. This is accomplished mainly by providing a driven shaft adapted to carry a removable grinding or cutting device for being disposed internally of an engine cylinder, and the shaft with the grinding or cutting device is caused during their rotation to move in the radius of a circle so that a device of a given size may be employed for grinding or reborning engine cylinders of various diameters.

Other objects of the invention are to provide a frame with a circular opening in which the shaft is movable; to provide in the opening of the frame a rotatable annular guide for causing the shaft to circumscribe a circle when driven; to provide on the shaft a fixed eccentric element which is rotatable with the rotation of the annular the guide as well as being arranged within the guide for positioning the shaft eccentrically with relation to the center of the opening of the annular guide; to provide means whereby the eccentric element may be adjusted within the guide so that shaft will be shifted to different positions eccentrically within the guide to vary the radial movement of the shaft; to provide mechanism to drive the shaft and the grinding or cutting device; to provide means for rotating the annular guide and the eccentric element whereby the shaft and grinding or cutting device during their rotation will be also radially moved; and to provide on the frame an adjusting

device which is operable for causing the shaft when driven to be moved at intervals lengthwise of the interior of the engine cylinder so that the grinding process will be accomplished evenly from one part to an opposite part of the cylinder.

A further object of the invention is to provide a machine for grinding and reborning engine cylinders of an efficient and durable construction which may be made in any desired size of any suitable material.

With these and other objects in view, the invention will be hereinafter more particularly described with reference to the accompanying drawings forming a part of this specification in which similar characters of reference indicate corresponding parts in all the views, and will then be pointed out in the claims at the end of the description.

In the drawings Figure 1 is a side elevation partly broken away, of one form of machine for grinding and reborning engine cylinders embodying my invention.

Fig. 2 is a top plan of the machine.

Fig. 3 is an enlarged fragmentary detail sectional view taken on the line 3-3 of Fig. 4.

Fig. 4 is an enlarged fragmentary sectional view, partly in detail, taken on the line 4-4 of Fig. 3, and

Fig. 5 is an enlarged fragmentary view, partly in detail and partly in section, taken on the line 5-5 of Fig. 2.

The machine has a frame 10 which may be of any suitable form, though the type illustrated consists of a substantially L-shaped base, as 11, providing a longitudinally disposed arm or plate 12 and an upwardly projecting arm or plate 13. In the longitudinal plate 12 of the base 11 may be an opening or slot 14 to allow the frame to be bolted or otherwise secured on a suitable support for holding the machine when in use. Projecting rightangularly from the plate 13 of the base in an opposite direction to the plate 12 is a hollow head 15 which may be composed of two superposed plates 15^a and 15^b having flanged edges in contact with each other to provide a groove 15^c which communicates with the interior of the head, and through the central parts of the plates are registered openings 16. Projecting upwardly from the top of the head 15 and on alignment radially with respect to the center of the opening 16 is a stationary bracket, as 17 composed of a vertical bar 17^a

- of a length so that it extends some distance above the head. Protruding from the lower end of the bar 17^a of the bracket toward the opening 16 of the head 15 is a lug 17^b with 5 an opening 17^c therein, while protruding from the top of the bar also toward the opening 16 is a similar lug 18 having an opening 18^a which is in register with the opening 17^c of the lug 17^b of the bracket.
- 10 Projecting on an upward incline from the upper part of the plate 13 of the base 11 of the frame and in an opposite direction to the head 15 is a bar 20 having an arm 21 extending laterally relative to one side of the 15 frame. At the intersection of the plate 13 with the head 15 of the frame are two spaced bearings 22 and 23 between which is a space 24 in communication with the opening 16 of the head 15.
- 15 Through the opening 16 of the head 15 of the frame is a shaft 25 which is disposed in spaced parallel arrangement relative to the bar 17^a of the bracket 17, and this shaft is movable downwardly and upwardly as 20 well as being rotatable. The shaft 25 is of a length so that its lower end portion may be moved considerable distance below the head 15 of the frame, and in the upper part of the shaft is a lengthwise slot 26.
- 25 Held on the upper end of the shaft 25 is a peripherally grooved wheel or sleeve 26^a which is revolvably arranged in the slot 27 provided lengthwise in one end of a bar 28 having on its second end an interiorly 30 threaded sleeve 29. The sleeve 29 of the bar 28 is rotatable on a threaded rod or bar 30 having its ends revolvble in the openings 17^c and 18^a of the lugs 17^b and 18 of the stationary bracket 17. The upper end of 35 the shaft 25 is thereby journaled in the bar 28, and as this bar is movable in downward and upward directions when the threaded rod 30 is accordingly rotated the shaft is adapted to be moved downwardly and up- 40 wardly through the opening 16 of the head 15 of the frame 10 as well as being adapted to be swung in the radius of a circle during the rotation of the shaft, as will be herein- 45 after more fully explained. To allow the 50 upward movement of the shaft to be limited when suitably arranged in the frame on the rod 30 above the sleeve 29 of the slotted bar 28 is an adjustable nut 31 having a laterally projecting pin 32 to serve as a handle 55 for manipulating the nut when being ad- justed. By positioning the nut at the proper height on the threaded rod 30 the sleeve 29 of the slotted bar 28 will be limited in its upward movement on the rod 30, and in 60 turn the upward movement of the shaft 25 will likewise be limited.
- The shaft 25 is normally disposed through the opening 16 of the head 15 of the frame eccentrically with relation to the center of 65 the opening, and the shaft is maintained in such position in the opening by an eccentric element, as 32. The eccentric element is preferably composed of a rotatable annular eccentric guide or band 33 with worm teeth 34 in its exterior periphery, and this band 70 surrounds the shaft 25 as well as being of a width so that it is spaced from the shaft besides being of a diameter so that its periphery revolves in the groove 15^c of the head 15 of the frame whereby the teeth 34 75 of the band will pass across the opening 24 between the bearings 22 and 23 of the frame. Within the guide or band 33 is a disk 35 which is rotatably adjustable in the band, and eccentrically with respect to the axial 80 center of the disk is an opening through which the shaft revolvably passes. Projecting upwardly from the disk around its opening is a boss 36 encircling the shaft, while extending downwardly from the underside of the eccentric guide or disk 35 also around its opening may be a sleeve or boss 37 which encircles the shaft. The boss 37 is preferably somewhat larger in diameter than the shaft 25, and within this boss is a 90 fixed bushing 38 in which the shaft is journaled so that the shaft is adapted to be moved in downward and upward directions through the bushing 37, through the opening of the disk 35 and through the boss 36 as 95 well as being revolvble. The guide band 33 and the eccentric disk 35 are releasably locked together by providing in the top of the disk adjacent to its periphery a row of spaced holes or sockets 38, and on the band 100 33 is a lug 39 arranged so that one of its ends overhangs the disk above the spaced sockets 38. In an opening in the overhanging end of the lug 39 is movably provided a screw pin, as 40, which is removably seated in one 105 of the sockets 38 of the disk 35. This disk is thereby adapted to be adjusted rotatably in the band 33 by removing from one of the sockets 38 the pin 40 after which the disk is suitably adjusted rotatably in the 110 band, and the pin is then inserted in another one of the sockets of the disk according to its adjusted position. By arranging the disk 35 and the band 33 in this manner both are revolvble in unison for causing the shaft 115 25 to move in the radius of a circle when the shaft is revolved, and this arrangement also permits the disk to be adjusted in the band 33 for shifting the shaft to various 120 positions relative to the center of the opening 16 of the head 15 of the frame 10 so that the shaft may be adjustably positioned to move in the path of circles of different radii simultaneously with its rotation. The end of the shaft 25 below the bushing 38 may be threaded, and on this threaded part may be two coöperating nuts 42 and 43 serving to allow a grinder, as 45, to be detachably fastened on the shaft. The grinder 45 may be in the form of a wheel of emery, carbo- 125 130

rundum or other material, or instead of a grinding wheel I may employ a cutting device having one or more blades whereby carbonaceous deposits on the interior of the cylinder, as 46, of an engine especially of an internal combustion type may be removed or the cylinder may be reborod as occasion requires.

The grinder or cutter is not claimed as 10 part of my invention, since it is obvious that various types of such devices may be used in conjunction with the machine.

In order to drive the shaft 25 any suitable means may be provided, though I prefer to 15 employ a form of mechanism, as 47. The mechanism 47 consists of providing on the frame 10 above its base 11 and between the head 15 and bar 20 two plates, as 48 and 49, which are spaced one above the other. These 20 plates are substantially T-shaped to provide each plate with an arm 50 having a cross-arm 51, and lengthwise of the arms 50 of the plates are registered slots 52. Between the cross-arms 51 of the plates 48 and 49 are 25 two spaced pulleys 53 and 54 one at each side of the registered slots 52 of the arms 50, and in the registered slots is a movable revoluble stud 55 having a pulley 56 disposed between the plates. The free ends of 30 the arms 50 of the plates 48 and 49 are connected by a plate 57 and in spaced openings in the plate 57 are two movable rods 58 and 59. One end of the rod 58 is held to the pin 55 below the pulley 56, while one end 35 of the rod 59 is held to the pin above the pulley 55. The rods 58 and 59 are of lengths so that their second end parts extend some distances beyond the plate 57 outwardly from between the T-shaped plates 48 and 49, and 40 on the free ends of the rods are heads or nuts 60. On the rod 58 between its head 60 and the plate 57 of the T-shaped plates is a spring, not shown, while on the rod 49 between its head 60 and the plate 57 is a spring 45 62, and both of these springs are tensioned for serving to yieldingly force the rods together with pin 55 and pulley 56 from the pulleys 53 and 54 toward the plate 57 of the T-shaped plates 48 and 49. On the shaft 50 25 above the boss 36 of the eccentric disk 35 is a pulley 63 having a laterally projecting lug 64 which is disposed in the slot 26 of the shaft so that the pulley when revolved will rotate the shaft, but the pulley 55 and its lug are loose on the shaft to allow the shaft to be moved downwardly and upwardly through the pulley. On the pulley 63 is a belt 65, part of which passes over the pulley 54, then over the pulley 56 and over 60 the pulley 53. The opposite part of the belt may be free of the pulleys 53, 54, 56, and the belt passes over a pulley 66 provided on the shaft 67 of an electric motor 68 which may be of any well known or preferred type, 65 and this motor, which may be driven from

any suitable source of electricity supply is fixed to a bar 69 attached to the arm 21 of the inclined bar 20 of the frame of the machine. When the motor is operated the belt 65 will be driven and the pulley 63, 70 shaft 25 and grinder 45 will likewise be rotated.

Serving as means to cause the shaft 25 and grinder 45 to be swung in the radius of a circle while being revolved, journaled in the 75 bearings 22 and 23 of the head 15 of the frame is a shaft 70 which is of a length so that one of its ends extend beyond the bearing 22. On the part of the shaft 70 in the space 24 of the head 15 is a worm 71 meshing with the worm teeth of the band 33 of the eccentric 32, and on the protruding end of the shaft 70 is a pulley 72 carrying a belt 73 which passes over a pulley 74 provided on the shaft 37 of the motor 68. With 80 the operation of the motor for rotating the shaft 25 and grinder 45 the pulley 74 will rotate to drive the belt 73, pulley 72, shaft 70 and worm 71. The band 33 and the disk 35 of the eccentric 32 will then be revolved 85 in unison with the rotation of the shaft 25 and grinder 45, for causing the shaft 25 with the grinder to also circumscribe a circle. By adjusting the disk 35 to various positions in the band 33, as hereinbefore explained, the position of the shaft will be varied relative to the center of the opening in the band 33, and the shaft and grinder will thereby be caused to move in different radii, as occasion requires, so the grinder 100 when of a given size may be used for grinding and reborod engine cylinders of different diameters.

In order to cause the shaft 25 and grinder 45 to be gradually moved lengthwise of the 105 interior of the engine cylinder during their operation, an adjusting device, as 75, is provided. This adjusting device consists of providing at the lower end of the bar 30 four spaced pins or fingers 76, 77, 78, 79 110 which protrude in lateral directions from parts of the bar corresponding to quadrants thereof, and these pins are in the path of movement of four spaced pins 80, 81, 82, 83 which protrude upwardly from parts corresponding to quadrants of the eccentric band 33 as well as being disposed around the eccentric disk 35. When the band 33, disk 35, shaft 25 and grinder 45 are driven, as above explained, the pins 80, 81, 82, 83 115 will consecutively contact with the pins 76, 77, 78, 79 of the bar 30, and this bar will be rotated for causing the slotted bar 28 to be moved downwardly on the bar 30. The shaft 25 will then be gradually moved like- 120 wise in the boss 36, disk 35 and boss 37 of the eccentric element 32 for causing the grinder to grind or reborod the engine cylinder evenly throughout its length. In order to readjust the shaft 25 with the grinder 125

45 to their normal positions on the upper end of the bar 30 of the bracket 17 is provided a handle 84. By holding the nut 31 of the bar 30 in proper position, and rotating the handle 84 accordingly the bar 30 will be revolved for causing the slotted bar 28 to move upwardly on the bar 30, and in turn the shaft 25, and grinder 45 will be reversely moved to their positions prior to 10 being moved downwardly during the grinding or reboring process.

In the foregoing description, I have embodied the preferred form of my invention, but I do not wish to be understood as limiting myself thereto as I am aware that modifications may be made therein without departing from the principle or sacrificing any of the advantages of this invention, therefore, I reserve to myself the right to make 20 such changes as fairly fall within the scope thereof.

Having thus described my invention, I claim as new and desire to secure by Letters

Patent:—

25 1. The combination, in a machine of the class described, of a hollow stationary head with registered openings leading from its interior, an annular guide element rotatable in the head, a shaft for being disposed interiorly of an engine cylinder and the shaft being eccentrically journaled within the guide as well as being also adjustable and 30 slidable in the guide, mechanism for driving the shaft, mechanism operable in unison with the operation of the driving mechanism whereby the guide element will be revolved for moving the shaft in the radius of a circle while being rotated, and an adjusting device operable with the driving of the shaft 35 for causing the shaft to move lengthwise of the engine cylinder at intervals during their rotation.

2. The combination, in a machine of the class described, of a hollow stationary head 45 with registered openings leading from its interior, an annular guide element rotatable in the head, a slidably rotatable shaft for being disposed interiorly of an engine cylinder and the shaft being journaled in the 50 guide as well as being disposed eccentrically with relation to the center of the registered openings of the head, mechanism for driving the shaft, means operable in unison with the operation of the mechanism whereby the 55 guide element will be revolved for moving the shaft in the radius of a circle while being rotated, means associated with the guide element for adjusting the shaft in various eccentric positions in the guide element 60 and in the registered openings, and an adjusting device operable with the driving of the shaft for causing the shaft to move lengthwise of the engine cylinder at intervals during their rotation.

65 3. The combination, in a machine of the

class described, of a frame having a circular opening, an annular guide element rotatable in the opening of the frame, a slidably rotatable shaft for being disposed interiorly of an engine cylinder and the shaft being 70 journaled in the frame as well as being disposed through the opening of the frame, an eccentric rotatably movable in the guide element for positioning the shaft eccentrically with relation to the center of the opening, 75 mechanism for driving the shaft, means operable in unison with the operation of the mechanism whereby the guide element will be revolved for moving the shaft in the radius of a circle while being rotated, means 80 adjustably connecting the eccentric to the guide element for adjusting the shaft in various eccentric positions in the guide element, and an adjusting device operable with the driving of the shaft for causing the 85 shaft to move in the frame lengthwise of the engine cylinder at intervals during their rotation.

4. The combination, in a machine of the class described, of a frame having a circular opening, a slidably rotatable shaft for being disposed interiorly of an engine cylinder and the shaft being journaled in the frame as well as being disposed through 90 the opening of the frame, an eccentric rotatable in the opening of the frame for positioning the shaft eccentrically with relation to the center of the opening, mechanism for driving the shaft, means operable in unison with the operation of the mechanism whereby the eccentric will be operated to move the shaft in the radius of a circle while being rotated, and an adjusting device operable with the driving of the shaft 95 for causing the shaft to move in the frame 100 lengthwise of the engine cylinder at intervals during their rotation.

5. The combination, in a machine of the class described, of a frame having a circular opening, an annular toothed guide element rotatable in the opening of the frame, a slidably adjustable shaft for being disposed interiorly of an engine cylinder and the shaft being journaled in the frame as well as being disposed through the opening 110 of the frame, a disk on the shaft and adjustably rotatable in the opening of the frame for positioning the shaft eccentrically with relation to the center of the opening, mechanism for driving the shaft, means 115 operable in unison with the operation of the mechanism whereby the guide element and disk will be revolved for moving the shaft in the radius of a circle while being rotated, means associated with the guide element and disk for adjusting the disk whereby the 120 shaft will be adjusted in various eccentric positions in the guide element, and an adjusting device operable with the driving 125 of the shaft for causing the shaft to move in 130

the frame lengthwise of the engine cylinder at intervals during their rotation.

6. The combination, in a machine of the class described, of a frame having a circular opening, an annular toothed guide element rotatable in the opening of the frame, a shaft for being disposed interiorly of an engine cylinder and the shaft being journaled in the frame as well as being disposed

10 through the opening of the frame, a disk fixed on the shaft and adjustably rotatable in the opening of the frame for positioning the shaft eccentrically with relation to the center of the opening, a bracket on the

15 frame, a motor on the bracket for driving

the shaft, means manually operable in unison with the operation of the motor whereby the guide element and disk will be revolved for moving the shaft in the radius of the circle while being rotated, and means associated with the guide element and disk for adjusting the disk whereby the shaft will be adjusted in various eccentric positions in the guide element.

This specification signed and witnessed 25 this 29th day of November, A. D. 1919.
